UNITED STATES PATENT OFFICE.

HENRY B. RUDISILL, OF ANNISTON, ALABAMA.

WROUGHT IRON OR STEEL CORE BAR.

Application filed June 3, 1926. Serial No. 113,430.

My invention relates to core bars and particularly to core bars of the type used in the manufacture of cast iron pipe and tubular cast articles.

Heretofore core bars for cast iron pipe have been made of double extra strong wrought iron or steel pipe having a cast iron head mounted on one end thereof. Where such core bars are designed for the production of 2" cast iron pipe, the core bar has been made of 1" double extra strong pipe, and in the practical use of such core bars considerable difficulty is encountered in unloading them when the molten iron, in pouring the cast iron pipe, gains access to and passes through the vent holes into the core bar. The internal diameter of such core bar pipe being approximately $\frac{1}{2}$ " makes it possible to use only a small diameter and relatively weak rod or bar for driving out the iron in the core bar or unloading it, and this has resulted in the frequent scrapping of such core bars which entails substantial loss due to the relatively high cost per foot of double extra strong wrought pipe.

I have conceived that wrought iron or steel pipe can be more successfully used in the production of core bars if instead of a single double extra strong pipe two wrought metal pipes telescoped together are substituted to form the core bar. Thus, for a 2" core bar, I propose the use of an outer extra strong wrought iron or steel pipe which has an inside bore of about $\frac{3}{4}$ " diameter, and I insert within same a smaller pipe such as a $\frac{1}{2}$ " standard pipe which has an inside diameter of $\frac{1}{2}$ " and an outside diameter of about $\frac{5}{8}$ of an inch. These two pipes will fit snugly when assembled and are riveted to hold them in position so that the vent holes with which they are provided will register.

As a result of this arrangement when my assembled double pipe core bar requires unloading, the inner pipe can be removed, unloaded and replaced, or a new inner pipe may be substituted, in which latter event the loss by scrapping is but a fraction of the loss where double extra strong pipe is scrapped.

Moreover, the inner pipe can be readily driven out for unloading after the rivet assembling it in the outer pipe has been cut, because a bar or rod having almost a $\frac{3}{4}$ " diameter can be used in the outer pipe to drive the inner pipe out.

I have also found that core bars made up of assembled pipe in the manner above described will not break in straightening as readily as a single double extra strong pipe core bar.

A further object of my invention is to provide inwardly converging tapering vent holes in the outer pipe which register with uniform diameter holes bored through the inner pipe, the registering holes providing ample venting for the core bar.

My invention further comprises the novel features of construction and arrangements of parts, which are hereinafter more particularly described and pointed out in the appended claims, reference being had to the accompanying drawings which form a part of this specification, and in which only the preferred embodiment of my invention is illustrated.

According to the drawings:—

Fig. 1 is a plan view of a core bar made up in accordance with my invention.

Fig. 2 is a cross-sectional view taken on the line 2—2 of Fig. 1.

Fig. 3 is a longitudinal cross-sectional view enlarged and partly broken away, taken on the line 3—3 of Fig. 1.

Similar reference numerals refer to similar parts throughout the drawings.

In the embodiment of my invention illustrated, I show a core bar intended for use in the manufacture of cast iron pipe, but it will, of course, be understood that my invention contemplates the designing and arranging of such core bar or arbor for various other analogous uses. The typical core bar selected to illustrate my invention is suited for the production of 2" cast iron pipe and I show the same as comprising an outer 1" extra strong wrought iron or steel pipe 1 cut to the desired length and having mounted thereon a cast iron head 2 of any standard design which is made fast thereon in accordance with the established practice. Within the pipe 1 I insert a smaller pipe 3, preferably a standard $\frac{1}{2}$ " wrought iron or steel pipe, which will have a diameter that will permit it to be readily inserted in the bore of the pipe 1 and secured in fixed relation thereto by means of a rivet 4. In the outer pipe 1 I provide a series of vent holes 5 which are drilled tapering so as to converge inwardly towards the bore of the pipe 1 and in the pipe 3 I provide a series of 110

vent holes 6 which are drilled straight and of even diameter and disposed to register with the vent holes 5.

Having assembled the core bar in the manner described in use, it will be found that it can be more easily straightened without breaking than the single pipe core bars and that when, due to the molten metal running through the vent holes 5 and 6 it becomes necessary to unload the core arbor, this can be done readily by cutting the rivet 4 and driving the inner pipe 3 out of the pipe 1. As this occurs the pipe 3 shears the necks of the metal in the holes 5 and 6 so that the taper plugs remaining in the taper holes 5 can be readily knocked out with a hammer using a tapered steel punch where necessary. The smaller pipe 3 when removed can be as readily unloaded as the double extra strong single pipe core bars because it will have the same internal diameter, but, when it cannot be readily unloaded, this inner pipe 3 can be scrapped and another pipe substituted with marked saving due to the fact that the standard $\frac{1}{2}$ " pipe 3 costs about 20 percent of the double extra strong 1" pipe. Thus, my improved assembled pipe core bar will not only provide pipe foundries with a better core bar but will also materially reduce their operating costs because of its lower maintenance cost and replacement expense as compared to the present core bars.

Though I have described with great par-

ticularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. A core bar of the character described, comprising assembled inner and outer pipes secured together and provided with registering vent holes, and a head mounted on one end of the assembled pipes.

2. A core bar of the character described, comprising two assembled pipes, the outer being an extra strong wrought metal pipe and the inner a standard wrought metal pipe, means to fasten the pipe together, and a head mounted on said outer pipe, there being registering vent holes through the pipes.

3. A core bar according to claim 2, in which the vent holes taper inwardly in the outer pipe and are of uniform diameter in the inner pipe.

4. A core bar according to claim 2, in which the means to fasten the pipes together consists of a rivet through the end of the assembled core bar remote from the head.

In testimony whereof I, HENRY B. RUDISILL, affix my signature.

HENRY B. RUDISILL.
